UNITED STATES PATENT OFFICE.

WILLIAM RODIGER, OF CHICAGO, ILLINOIS.

FOUNTAIN-PEN FILLER.

1,109,249.

Specification of Letters Patent.

Patented Sept. 1, 1914.

Application filed March 18, 1911. Serial No. 615,277.

To all whom it may concern:

Be it known that I, WILLIAM RODIGER, a citizen of the United States, residing at Chicago, in the county of Cook and State 5 of Illinois, have invented certain new and useful Improvements in Fountain-Pen Fillers, of which the following is a specification.

This invention relates to an improvement in fountain pen fillers, and consists substantially in the construction and arrangement 10 hereinafter described, shown in the accompanying drawings, and more particularly pointed out in the claims.

Like letters refer to the same parts in the 15 several figures of the drawing, in which—

Figure 1 is a vertical section of the fountain pen filler closed in readiness for transportation. Fig. 2 is a vertical section with the lower portion broken away and with the 20 stopper removed and the pen in position to be filled. Fig. 3 is a horizontal section on the line 3—3, Fig. 1, and with a part of the top portion of the vessel broken away.

In order that the invention may be fully 25 understood it will be described more particularly in connection with the accompanying drawing and afterward the novelty will be pointed out in the claims.

The ink bottle proper is made of any desirable shape and suitable material such as 30 is usual in devices of this class and is designated in the accompanying drawing by the reference letter A. In the neck and mouth of this bottle there is inserted a filling tube, 35 into which the pen is to be inserted as shown in Fig. 2 of the drawing, and this filling tube is preferably made of rubber having a vertical opening through it of sufficient length to hold the fountain pen in the act of 40 being filled and of material with some elasticity and yet sufficient firmness to serve the purpose, such for instance, as rubber. This tube is designated by the reference letter B in the drawings, and is preferably provided 45 with a horizontally extending flange X, adapting it to rest on the flange of the mouth of the bottle, and with a smaller flange or bead at its lower end, indicated by the letter Y, which hooks under the lower edge of 50 the mouth of the bottle where such edge joins the cover or roof of said bottle. The two being made of elastic material, the flange or bead Y may be compressed so as to permit the tube to be inserted with- 55 in the mouth of the bottle and after such insertion this flange will bear, as before

stated, against the lower edge of this mouth of the bottle and thus retain the tube in position. A stopper of any suitable material, but which is preferably made of rubber, is likewise provided to close the filling tube when it is not in use, and this stopper may have an annular bead as indicated in dotted lines in Fig. 1, to engage an annular recess on the interior of the tube and thus hold the stopper in position.

Secured to the lower end of the bottle is a flexible bottom C, which is preferably made of rubber, and comprises a vertical cylindrical barrel, an upper horizontal flange 70 and a lower horizontal closure or diaphragm D. The lower edge of the ink receptacle rests upon the upper horizontal flange of this rubber bottom and preferably in an annular seat provided for the purpose. The cylindrical barrel extends vertically below this horizontal flange and below the lower edge of the receptacle and serves as the compressible portion of the bottom. This rubber bottom terminates in a horizontal closure or diaphragm. The rubber bottom is therefore capable of being collapsed or compressed by a pressure exerted upon its horizontal diaphragm, the sides then acting like the sides of a bellows. This rubber bottom is secured to the bottle in any suitable way, but a convenient construction for the purpose is a metal ferrule, indicated in Fig. 1 of the drawing at E, which is preferably screw-threaded at its top to engage 80 corresponding threads on the bottom of the vessel, and has a hooked flange F at its bottom which is placed under and supports the rubber bottom as illustrated in the drawing.

When it is desired to fill the fountain pen the latter is placed as shown in Fig. 2 in the tube, and then the receptacle for the ink is inverted and the operator manipulates the rubber bottom by pressing upon it with his fingers, which causes the sides of such bottom to act like the sides of a bellows and compress air in the receptacle upon the ink and thus force the latter into the pen.

It is obvious that modifications in the details of the device may be made by those 105 skilled in the art without departing from the principle of the invention, and therefore I do not wish to be understood as confining myself to the exact details shown.

What I claim, and desire to secure by Letters Patent, is:

1. A fountain pen filler comprising a re-

- ceptacle having an inelastic body portion, and an elastic tube secured to one end of said body and adapted to receive the fountain pen, and an elastic and compressible member secured to the other end of the body.
5. A fountain pen filler comprising a receptacle having an inelastic body portion, a rubber bottom for the same comprising a seat at its upper end, a diaphragm at its lower end and cylindrical sides connecting such seat and diaphragm and adapting such bottom to be compressed when desired in combination with means for securing the bottom to the body portion of the receptacle.
10. 3. A fountain pen filler comprising a receptacle containing an inelastic body portion, a rubber bottom for the same comprising a seat at its upper end, and a bearing against one edge of such body portion, and 20 having a diaphragm connected by flexible side walls to the seat, thus adapting said bottom to be manipulated to give the desired movement to the ink to fill the fountain pen.
15. 4. A fountain pen filling device comprising a receptacle, having an inelastic body

portion, and an elastic tube secured to one end of said body portion and adapted to receive the fountain pen and an elastic and extensible member secured to the other end 30 of the body portion.

5. A fountain pen filling device, comprising a receptacle having at one end elastic means adapted to receive the fountain pen, and an elastic member capable of extension 35 and contraction secured to the other end of the receptacle.

6. A fountain pen filling device comprising a receptacle having an inelastic body portion, and an elastic tube secured to one 40 end of said body portion and adapted to receive the fountain pen, and an elastic and compressible detachable member secured to the other end of the body portion.

In testimony whereof I have signed my name to this specification, in the presence of two subscribing witnesses, on this 15th day of March, A. D. 1911.

WILLIAM RODIGER.
